UNITED STATES PATENT OFFICE.

JAMES LEWIS WOLLESON, OF CHICAGO, ILLINOIS.

POWDER DUSTER.

Application filed March 10, 1922. Serial No. 542,722.

To all whom it may concern:

Be it known that I, JAMES L. WOLLESON, a citizen of the United States, residing at Chicago, in the county of Cook and State 5 of Illinois, have invented a new and useful Powder Duster, of which the following is a specification.

This invention relates to containers, and more particularly to pasteboard boxes 10 especially designed for containing powdered substances.

The primary object of the invention is to provide means to be positioned within a box, prior to the filling of the same, whereby 15 the box may be used as a bellows for forcing the powdered material therefrom.

A further object of the invention is to provide a device of this character which may be readily and easily positioned within 20 a box, eliminating the necessity of changing the construction of the box to position the device.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:

Figure 1 is a sectional view through a 35 container disclosing a device constructed in accordance with the present invention as positioned therein.

Figure 2 is a plan view of the spring device.

Figure 3 is an end elevational view of the device.

Referring to the drawing in detail, the device embodies a length of wire bent to form an upper section 5 and a lower section 6. The wire is also formed into an intermediate coiled portion 7 which is disposed between the sections 5 and 6 adjacent to one end thereof.

Each of the sections includes an arm 8 formed with a hook at one end thereof, to grip the right angled portion 9 of the sec-

tion to secure the end of the arm to the right angled portion 9.

An arm 10 also forms a part of each section, and forms a relatively straight edge to conform to the end wall of a container to closely fit within the same. As shown, the coiled spring 11, which is formed integral with the length of wire, is disposed at the inner ends of the right angled portions 9 so that the coiled portion will lie within a container at a point remote from the ends of the box, permitting the sides of the box to be compressed.

From the foregoing it will be seen that a box supplied with a spring device of this character, may have its side walls pressed inwardly to cause material contained in the box to be forced outwardly therefrom, the coiled spring 11 acting to return the side walls of the box to their normal positions. It is to be understood that it is contemplated to employ this device in connection with pasteboard boxes or containers, wherein an opening may be formed in one end of the container to permit the material to pass outwardly, from the container when the side walls are compressed and released at intervals.

Having thus described the invention, what is claimed as new is:

In a device of the character described, a container, a length of wire bent to provide an upper section and a lower section to be fitted in the container, each of said sections including side members, said length of wire having portions extending at right angles to the side members, a coiled portion at the ends of the right angled portions and disposed between the sections and hook members formed at the ends of the said length of wire and adapted to hook over portions of the right angled portions of the wire to hold the sections in position.

In testimony that I claim the foregoing as my own, I have hereto affixed my signature in the presence of two witnesses.

JAMES LEWIS WOLLESON.

Witnesses:

WALTER A. ENDER,
ERNST STOTZLER.
